The ornamental design for a novelty headwear, as shown and described.

DESCRIPTION

FIG. 1 is a perspective view of the novelty headwear shown in condition for wearing.

FIG. 2 is a front elevational view of the novelty headwear.

FIG. 3 is a top plan view of the novelty headwear.

FIG. 4 is a bottom plan view of the novelty headwear.

FIG. 5 is a rear elevational view of the novelty headwear.

FIG. 6 is a side elevational view of the novelty headwear taken from the right side of FIG. 1; and,

FIG. 7 is a side elevational view of the novelty headwear taken from the left side of FIG. 1.

The broken lines shown in the drawings depict unclaimed features.
